(57) **CLAIM**

The ornamental design for a cradle as shown and described.

DESCRIPTION

FIG. 1 is a front perspective view of a cradle according to the present invention;

FIG. 2 is a rear perspective view of the cradle of FIG. 1; FIG. 3 is a front elevational view of the cradle of FIG. 1; FIG. 4 is a rear elevational view of the cradle of FIG. 1; FIG. 5 is a left side elevational view of the cradle of FIG. 1; FIG. 6 is a right side elevational view of the cradle of FIG. 1;

FIG. 7 is a top plan view of the cradle of FIG. 1; and, FIG. 8 is a bottom plan view of the cradle of FIG. 1. The broken lines shown in FIGS. 1-8 depict portions of the cradle that form no part of the claimed design.

1 Claim, 8 Drawing Sheets
